DISPENSER FOR GROUND AND POWDERED MATERIALS

Hans Joseph Cortner, New York, N. Y.

Application December 10, 1954, Serial No. 33,483

Term of patent 14 years

(Cl. D52—2)

Fig. 1.

Fig. 2.

Fig. 3.

Fig. 1 is a front perspective view of a dispenser for ground and powdered materials, showing my new design;

Fig. 2 is a top view thereof; and

Fig. 3 is a side view thereof.

The opposite side of the dispenser is substantially the same in appearance as the side shown, but is devoid of the lever.

I claim:

The ornamental design for a dispenser for ground and powdered materials, as shown and described.
